H. SHOEMAKER.

CROSSHEAD.

APPLICATION FILED NOV. 10, 1921.

1,436,915.

Patented Nov. 28, 1922.

Fig. 1.

UNITED STATES PATENT OFFICE.

HARVEY SHOEMAKER, OF WOLLASTON, MASSACHUSETTS.

CROSSEHEAD.

Application filed November 10, 1921. Serial No. 514,194.

To all whom it may concern:

Be it known that I, HARVEY SHOEMAKER, a citizen of the United States, and a resident of Wollaston, in the county of Norfolk and 5 State of Massachusetts, have invented a certain new and useful Improvement in Cross-heads, of which improvement the following is a specification.

This invention relates to engine cross heads and guides, and more particularly to that type in which the cross head slides upon cylindrical guide rods, the objects being to provide an improved and simple construction which may be readily taken down and 10 reapplied, to preserve accurate alignment, to provide increased bearing surface for the cross head on the guides, and to provide an improved wearing connection for the cross head which may be readily adjusted for taking 15 up lost motion and wear without the use of tools, jigs, or templets and at the same time maintain correct alignment of the cross head upon the guides.

One feature of my improvement comprises 20 a pair of tubular guides with binder bolts extending through the same for securing said tubes to the back cylinder head and to the guide yoke. Another feature comprises 25 split tubular bushings or gibs carried by the cross head and mounted on the guides. Still another feature comprises the use of thin 30 tubular shims surrounding the gibs for taking up lost motion due to wear.

In the accompanying drawing: Figure 1 is 35 a side view partly in side elevation and partly in section, showing a construction of cross head and guides embodying my improvement; Fig. 2, a transverse section taken on the line 2—2 of Fig. 1; Fig. 3, a trans- 40 verse section of the cross head shoe and guide taken on the line 3—3 of Fig. 1; and, Fig. 4, an end view showing the guide yoke.

According to the construction shown, the cross head, 5, which is preferably made of 45 cast steel, is formed with upper and lower portions or shoes having cylindrical openings for embracing the guides, 6, comprising hollow rods, preferably formed of steel tubing of the desired diameter. The hollow 50 guides are supported at one end by fitting within suitable sockets formed in the back head, 7, of the engine cylinder, and at the other end by extending into openings in the guide yoke, 8, the guides being securely held 55 in position by the binder or anchor bolts, 9,

extending through said tubular guides and tapped into the back cylinder head, the outer ends of said bolts being fastened by means of the clamps, 10, bolted to the guide yoke.

For the purpose of taking up the wear between the cross head and guides, I provide each shoe with a pair of concave or tubular bushings or gibs, 11, which may be split at one or both sides, and are formed with flanges, 12, which are clamped by means of the gib caps, 13, mounted by a screw thread connection upon each end of the shoe of the cross head. The gibs may be formed of bronze, gun metal, or hard babbitt, and as wear occurs between the gibs and the tubular guides, a thin tubular shim, 14, of tin, russia iron, or other sheet metal, may be inserted between the outer surface of the gibs and the inner surface of the opening through the cross head shoe. The shim preferably extends the full length of the shoe to form a lining therefor, and may be split throughout its length, in order that it may be put on over the tubular guide, 6.

The method of taking up lost motion is 80 very simple since it is only necessary to loosen the gib caps, 12, and insert a tubular shim, 14, or remove the worn gibs and replace them with others, or both of these operations as desired, and then reapply the gib 85 caps, 12, screwing the same up tight in order to securely clamp the gib flanges against the ends of the shoe. The gib caps may then be fastened by the set screws, 15. The cross head is provided with the usual piston rod 90 connection, 17, and a main pin, 16, for the main rod, (not shown), which is adapted to extend through the opening in the guide yoke in the usual manner.

The construction is exceedingly simple, 95 composed of but few parts, and can be readily taken down and again applied in a minimum time and with a minimum number of tools. Another important feature is the perfect alignment of the guides which do 100 not vary from correct line even when taken down and again applied. The bearing of the gibs in the cross head is also maintained in perfect alignment with the guides after the shims are inserted or after worn gibs are replaced with new ones. By means of my improved construction, an increased bearing area is obtained on the guides so that a shorter guide bearing is made possible, thereby reducing weight and expense.

Having now described my invention, what I claim as new and desire to secure by Letters Patent is:

1. The combination with cylindrical guides, of a cross head having shoes provided with openings for said guides, tubular gibs mounted in said openings, and means for clamping said gibs in position.
2. The combination with cylindrical guides, of a cross head having shoes provided with openings for said guides, a pair of tubular gibs mounted in each of said openings and having flanges at their outer ends, and gib caps for clamping said flanges.
3. The combination with cylindrical guides, of a cross head having shoes provided with openings for said guides, tubular gibs mounted in said openings, and a tubular shim surrounding said gibs.
4. The combination of a tubular guide for a cross head, a back cylinder head having a socket for supporting one end of said guide, a guide yoke supporting the other end, and a binder bolt extending through said tubular guide and fastened at its end to said back head.
5. The combination of a cylindrical tubular guide for cross heads, a back cylinder head having means for supporting one end of said guide, a guide yoke supporting the other end, and a binder bolt extending through said tubular guide and fastened at one end, and a binder bolt extending through said tubular guide and fastened to the cylinder head.
6. The combination of a cylindrical tubular guide for cross heads, a back cylinder head having means for supporting one end of said guide, a guide yoke supporting the other end, a binder bolt extending through said tubular guide and fastened at one end to the cylinder head, and means for securing the other end of said bolt to the guide yoke.
7. The combination of a cylindrical tubular guide for cross heads, a back cylinder head having means for supporting one end of said guide, a guide yoke supporting the other end, a binder bolt extending through said tubular guide and having a threaded connection to the cylinder head, and a clamp mounted on the guide yoke for fastening the other end of said bolt.
8. The combination with a pair of guides, having convex bearing surfaces, of a cross head having shoes provided with spaces for said guides, detachable gibs mounted in said spaces and having concave bearing surfaces, and means for fastening said gibs in position.

In testimony whereof I have hereunto set my hand.

HARVEY SHOEMAKER.
